[57] CLAIM

[**] Term: 14 Years

The ornamental design for a illuminated house number
or the like, as shown and described.

[21] Appl. No.: 575,503

DESCRIPTION

[22] Filed: Aug. 29, 1990

FIG. 1 is a perspective view of an illuminated house
number or the like showing our new design, with the
broken lines showing for illustrative purposes only and
forming no part of the claimed design;

[52] U.S. Cl. D20/17

FIG. 2 is a right side elevational view thereof, with the
opposite side being a mirror image;[58] Field of Search D20/10, 17, 39, 40,
D20/41, 42; 40/540, 541, 542, 451; 362/811,
812

FIG. 3 is a front elevational view thereof;

[56] References Cited

FIG. 4 is a rear elevational view of a second embodi-
ment thereof, wherein the only difference resides in the
omission of the upper tab attaching feature;
